UNITED STATES PATENT OFFICE.

WILLIAM F. ASHCRAFT, OF LOVELY DALE, INDIANA.

WASHING-MACHINE.

SPECIFICATION forming part of Letters Patent No. 236,927, dated January 25, 1881.

Application filed February 26, 1880.

To all whom it may concern:

Be it known that I, WILLIAM F. ASHCRAFT, of Lovely Dale, in the county of Knox and State of Indiana, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification.

Figure 1 is a side view. Fig. 2 is a longitudinal sectional view. Fig. 3 is a vertical cross-section. Fig. 4 is a view of the rubber, detached.

Corresponding parts in the several figures are denoted by like letters of reference.

This invention relates to washing-machines; and it consists in certain improvements in the construction of the same, which will be hereinafter fully described, and particularly pointed out in the claim.

In the drawings hereto annexed, A represents the tub or box, having a semi-cylindrical or segmental bottom, B, of wood or sheet metal, and provided at one end with an inclined drain-box, C, to receive the water squeezed out of the clothes in wringing the same, and carry it back to tub or box A, the wringer 30 being secured upon the cross-piece D, which separates the box from the drain-chamber.

The lower wash-board or rubber E is constructed of slats F F secured upon segmental strips G G, conforming to the curvature of the bottom. H H are coiled springs, arranged in the tub A and supporting the rubber E, which is thus enabled to yield and accommodate itself to the quantity of clothes in the box. One end of rubber E abuts against a ledge, I, at one end of the tub or box. The other end is provided with a stud, J, to which is attached one end of a strap, K, the other end of which is secured to the bottom of tub A. The rubber E, which in this manner is held securely in position during operation of the machine, may be readily removed by unbuttoning strap K from stud J, thus permitting the machine to be easily and thoroughly cleaned, when necessary.

50 The sides of the tub A are provided with cleats L L, beveled upon their inner adjoining

sides, thus forming dovetailed grooves in which slotted slides M M are capable of being vertically adjusted, set-screws N N being provided to retain them in any desired position. The 55 upper ends of the slides M M have bearings for the shaft O, carrying the oscillating-rubber P, which is constructed in the usual manner with grooves or corrugations upon its under side. At or near the center of its lower face the rubber P is provided with a transverse groove, Q, wider and deeper than the rest, to receive the lower side piece of a frame, R, which is pivoted upon the sides of the rubber, as shown. The upper side piece of frame R forms, it will be 65 seen, a handle, by which the lower side of the frame may be forced into or drawn out of the groove or recess Q.

S is a lever pivoted to the side of one of the rods or arms T connecting the rubber P with 70 shaft O. Said lever is provided with several notches, U U, adapted to engage the handle of frame R, and thus retain the said frame in any desired position.

V is a lever or latch, pivoted to the top of 75 box or tub A, for the purpose of holding the rubber P in position while clothes are being placed in the box.

From the foregoing description, taken in connection with the drawings hereto annexed, 80 the operation and advantages of my invention will be readily understood.

To adjust the clothes for washing, the rubber P is raised and supported upon the latch V, while the clothes are secured or clamped to 85 the rubber by means of the pivoted frame R. The rubber is then let down and the frame secured by the notched lever S. An oscillating motion is then imparted to the rubber P by means of a lever or handle attached to the 90 end of shaft O, and continued until the clothes shall have been thoroughly cleansed.

By raising or lowering the slides M M the rubber P may be raised or lowered, thus enabling any desired quantity of clothes to be 95 accommodated in the tub or box.

I am aware that the reciprocating rubber has been provided with a wire spring adapted to securing the clothes, in process of washing, to the under face of the said rubber, as is 100 shown in the Patent No. 120,310. While I have not adopted and do not claim this spring,

I have provided a pivoted frame, the lower cross-bar of which enters a transverse groove in the under face of the rubber, and is held in place to clamp the clothes by a notched lever, 5 as is plainly shown in the drawings. I make no claim herein to the clamping-spring above referred to.

Having thus described my invention, I claim and desire to secure by Letters Patent of the 10 United States— The combination, with the rubber P, having

transverse groove Q, of the pivoted frame R, and the notched lever S, substantially as and for the purpose herein shown and specified.

In testimony that I claim the foregoing as 15 my own I have hereto affixed my signature in presence of two witnesses.

WILLIAM F. ASHCRAFT.
